THE NORRIS PETERS CO., PHOTO-LITHO., WASHINGTON, D. C.

UNITED STATES PATENT OFFICE.

PHILIP CORRIGAN, OF WAKEFIELD, NEW YORK.

FURNACE.

SPECIFICATION forming part of Letters Patent No. 703,768, dated July 1, 1902.

Application filed March 30, 1901. Serial No. 53,722. (No model.)

To all whom it may concern:

Be it known that I, PHILIP CORRIGAN, a citizen of the United States, residing in Wakefield, in the borough of the Bronx, in the city 5 and State of New York, have invented a certain new and useful Improvement in Metallurgical Furnaces, of which the following is a specification.

I have in my experiments applied the improvement to furnaces of moderate size burning gas as a fuel and used for melting and refining precious metals and will describe it as thus applied. It presents the pipes conspicuously in sight under all conditions, allowing 15 constant inspection and easy access for adjustment or repairs when necessary, and especially provides for the easy removal and exchange of the burners through which the mixture of air and gas is projected into the 20 furnace.

I designate as "burners" the pipes usually arranged tangentially in the walls of the furnace. They correspond generally to the parts sometimes designated "twyers" in large furnaces for reducing and melting metals, the 25 inner end of each coinciding approximately with the inner face of the furnace, the main body lying within the wall and the outer end being adapted for joining to a pipe which supplies air and gas.

My burners may be in whole or in part of fire-brick, plumbago, or other refractory material; but the outer portion of each, being sufficiently distant from the heated locality, 30 may be ordinary cast-iron.

My invention allows for so easy exchange that I have in my experiments made each entire burner a single casting of ordinary soft iron.

The following is a description of what I consider the best means of carrying out the invention.

The accompanying drawings form a part of this specification.

Figure 1 is a side elevation. Fig. 2 is a horizontal section on the line 2 2 in Fig. 1 with portions shown in plan. The remaining figures show portions on a larger scale. Fig. 3 is a plan view, partly in horizontal section, 45 showing one of my burners and its connection to the other pipes. Fig. 3^a is an end view of the outer end, showing the mark by which

the position of the delivery-slot of the burner is clearly visible from the outside. Fig. 4 is a cross-section on the line 4 4 in Fig. 3. Fig. 55 5 is an end view of the delivery-nozzle of the burner. Fig. 6 is a horizontal section of the delivery end and the adjacent portion of the furnace on the same scale as in Fig. 3, showing a modification, a beveled end to the burner; 60 and Fig. 6^a shows the preferred plan for marking the outer end when such nozzle is used.

Similar letters of reference indicate corresponding parts in all the figures where they appear.

A is the base or bottom, A' the fire-brick lining, and A² the exterior brick or backing. These latter may usually be of ordinary brick; but the whole may, if desired, be fire-brick 70 in as many or few pieces as may be preferred.

C is a rectangular outer casing of cast-iron or other suitable material holding the whole reliably together. Two smooth tangential passages a a are provided on opposite sides 75 of the furnace, and in these my burners are inserted by being thrust inward from the outside.

D' D' designate the inner ends of my burners, each partially closed, but having a liberal slot d extending diametrically across.

D designates the main bodies tapered, as shown.

D² is a short screw-threaded portion matching the screw-threads in either i' or i², and D³ 85 a cylindrical open-work extension.

D⁴ is the closed outer portion, carrying a smaller continuation having its end D⁶ squared. A cross-mark d⁷ is cut on the outer face of the extreme end, which mark lies in 90 the same plane as the slot d at the inner end, so that the mark serves as an index to show how the slot is turned. The burner should always be adjusted with the slot d extending up and down, so that a flame having more 95 height than thickness shall result from the combustion of the gas as it flows from each slot into the furnace and spirals around therein. The inner ends of the burners presented to the interior of the furnace are the 100 parts which are liable to be destroyed by the heat.

The tapering bodies D of the burners are allowed to fit easily and may be left a little

loose, or the slight space around each may be packed with fire-clay or other refractory material. I prefer to leave the joint open.

B is the pipe, bringing air under pressure which has been forced by a blower, (not shown,) and O is a stop-cock controlling the flow. B' is a tapering nozzle, through which it is ejected with force into a pipe B², where it mingles with combustible gas received under a gentle pressure through a pipe E, controlled by a cock F, by the aid of a pump or blower. (Not shown.) The pipe B² extends across the front and thence rearward. At points therein on opposite sides of the furnace are two chambers I I, slightly larger than the pipe, each of which serves the important function of receiving a burner D, extending through it transversely and allowing such burner to be easily inserted, adjusted, and removed. Each chamber I has a screw-threaded hole i' in its outer side and a similar hole i² in its inner side. Each chamber I and its holes i' i² must be set in line with one of the tangentially-arranged holes a in the brick-work, which receive the inner end and main body of each burner.

Three or a larger number of similar burners D must be provided, so as to serve interchangeably. One is introduced in each chamber I, turning each properly to traverse the outer screw-threaded hole i', and again after a further thrust to properly enter and engage in the inner hole i². After it is "home" a detachable stuffing-box M, screw-threaded on its exterior, is slipped over the contracted end D⁶ D⁵ and engaged in the hole i' and screwed in. A ring of any convenient soft packing H is applied in its screw-threaded interior m, and a ring or gland G, screw-threaded on its exterior, is applied and turned to properly compress it. I have used asbestos as packing; but as there is little heat any packing which will make a fairly gas-tight joint will serve. The inner end D' of the burner should be about flush with the interior of the furnace. If it extends too much it is less able to withstand the heat, and it should not be too much drawn back. Unscrewing the stuffing-box M liberates the burner, so that the latter can be turned as many half-turns as required in either direction to adjust it farther in or out, taking care to always leave it with the mark d⁶ extending up and down, and always retightening the stuffing-box after such adjustment. The part M serves a double function—one as a stuffing-box and another as a jam-nut, which being screwed in with force insures the absolute fixity of the burner until it is again unscrewed.

The complete removal of the burner and the supplying of another may be effected in a very short time even when the furnace is at full heat. To effect this, I shut the cocks O and F, thus stopping the supply of air and gas, apply a wrench to the outer end of the jam-nut stuffing-box M, (flat places being

formed there to allow this without injuring the threads,) and remove that part. Then apply a proper wrench to the squared end D⁶ 70 and turn the burner, drawing it gradually back. When the screw-threaded portion D² is clear of the screw-threads in the inner orifice i², the burner may be moved directly outward until the screw-threads on D² contact 75 with the screw-threads in the outer orifice i', when the burner must be again turned until these threads are passed. Then it may be drawn out directly and its hot inner end examined. If exchange is expedient, a spare 80 burner is introduced in its place, and a reversal of the movements and a proper adjustment of the new burner and of the same stuffing-box jam-nut M, its packing H, and ring G, or of a new one of each, makes all ready, 85 and the gas and air being again turned on the furnace is again serving as before.

It is not essential that the air which is allowed to mix with the gas at the reduced nozzle B' shall be sufficient to attain complete 90 combustion. The force with which the mixture of air and gas is projected into the furnace draws in additional air through the small space around my tapering burner, and the air thus received at ordinary pressure in 95 addition to that received at the earlier stage at a pressure above atmosphere together should be a little more than sufficient to effect complete combustion.

The hole a being tapered and the burner D, 100 which fits loosely therein, being also tapered, it follows that the adjustment of the pipe D inward and outward by the means described will have the effect to modify the quantity of air which is drawn in at atmospheric pressure 105 around the burner, screwing the burner D in contracting the annular space and reducing the quantity of air admitted through it, and drawing out the burner D, enlarging such space, and increasing the quantity of air 110 thus admitted.

The general form of my furnace may correspond to one which has been long approved, having sliding doors K, arranged to be moved laterally on suitable ways to cover and uncover the furnace conveniently when desired. The flame from my burners travels spirally around in the interior of the furnace in the approximately annular space between the crucible W and the inner wall A' of the furnace and escapes through the flue a' into the chimney. (Not shown.)

My furnace is accessible for inspection or repairs in the ordinary manner. The provisions for controlling the air and gas may be 125 adjusted with great nicety and changed without difficulty, as conditions may require, while the furnace is working.

The most likely points to fail in a furnace of this general character are the inner ends 130 of the burners. My burner may be simply and cheaply constructed as a single casting, the only parts requiring to be finished being the screw-threads on D² and the stuffing-box.

A single stuffing-box may serve with a number of successive burners.

Modifications may be made without departing from the principle or sacrificing the advantages of the invention. The form of the casing C, constituting the exterior of the furnace, may be cylindrical or of various other forms instead of rectangular. In such case or in any case the pipe B may be curved instead of having straight portions, as shown. There may be three or four or only one instead of the two burners shown, providing a corresponding number of the other parts.

The inner end of the burner may, if preferred, be beveled, as shown in Fig. 6. This will allow it to coincide more perfectly with the inner surface of the fire-brick lining A' of the furnace; but it interferes with the nicety of adjustment, forbidding its being left half revolved. When such form is adopted, a mark not extending across, but on one side alone, as the prick-punch mark d', may be employed, by which to insure that it is correctly arranged.

It is not essential that the portion D³ of the burner be cylindrical, with bars extending longitudinally and all the spaces between open, as shown. It is only essential that it be not too large to allow the burner to be introduced and withdrawn by longitudinal movements and that it have liberal apertures—what is commonly termed “open-work”—there being metal connecting the outer and inner portions of the burner, but with sufficient spaces to allow the mixture of gas and air to freely traverse inward from the chamber I, and thence flow without obstruction to the nozzle and be discharged into the furnace.

I claim as my invention—

1. In a metallurgical apparatus, a furnace A having a tangential passage a leading from the outside of the furnace-wall to the interior space of the furnace and a supply-pipe B²

arranged to bring gases under pressure, a burner D adapted for being inserted and removed longitudinally of such passage, a screw-threaded portion D² on such burner, a stuffing-box on the exterior of the chamber, a further extension of the burner outward beyond the stuffing-box equipped to receive a wrench, and a chamber I in such supply-pipe having the screw-threaded portion i' matching the threads D², the portion D³ of the burner being open-work so as to constitute a strong extension of the burner across the chamber I, but so liberally apertured as to freely admit the gas and air, such apparatus being adapted to allow the burner to be adjusted outward and inward and to be removed and replaced when required without disturbing the other parts, all substantially as herein specified.

2. In a metallurgical apparatus having a furnace-lining A' with a passage a leading from the outside to the inside of the furnace-wall, and a supply-pipe B² arranged to bring gases under pressure, a chamber I in said supply-pipe having the internally-screw-threaded part i' and also having the internally-screw-threaded part i² for holding the burner and a burner D extending longitudinally of such passage and having the screw-threaded part D² thereon, in combination with each other and with the screw-threaded ring M m matched in the screw-threaded orifice i' on the outer side of said chamber, adapted to serve the double function of a stuffing-box and a jam-nut, all substantially as herein specified.

In testimony that I claim the invention above set forth I affix my signature in presence of two witnesses.

PHILIP CORRIGAN.
